UNITED STATES PATENT OFFICE.

SAMUEL B. FIELD, OF HOLBROOK, MASSACHUSETTS, ASSIGNOR TO PNEUMATIC SCALE CORPORATION, LIMITED, OF QUINCY, MASSACHUSETTS, A CORPORATION OF MAINE.

MOISTURE-PROOF PACKAGE AND PROCESS OF MAKING THE SAME.

1,264,497.

Specification of Letters Patent. Patented Apr. 30, 1918.

Application filed December 14, 1917. Serial No. 207,023.

To all whom it may concern:

Be it known that I, SAMUEL B. FIELD, a citizen of the United States, residing at Holbrook, Mass., county of Norfolk, State 5 of Massachusetts, have invented a certain new and useful Improvement in Moisture-Proof Packages and Processes of Making the Same, of which the following is a specification, reference being had therein to the 10 accompanying drawings.

The invention relates to an improvement in moisture proof sealed packages and in the method of producing the same. The object of the invention is to provide a moisture 15 proof wrapped and sealed package, the wrapping and sealing of which is relatively inexpensive, which is moisture proof under all ordinary exposures to the atmosphere, which is neat in appearance, which is ready 20 for display in its wrapped and sealed condition, and which when sold over the counter does not require any additional wrapping but is ready for delivery to the customer. One object of the invention also is 25 to produce such a package in an economical manner both by the use of relatively cheap material and by economy in the process of wrapping and sealing.

The invention may be applied to a closed 30 package which has first been put up in any ordinary way, as for instance putting the goods into an ordinary carton having end forming flaps which are closed and pasted if desired, or the goods may be put up in 35 a paste board box having a cover, or in a paper bag having the mouth closed by folding the projecting top end of the bag and preferably securing the top in a closed position by paste or tape or string or any other 40 suitable method. The sealing wrapper consists preferably of two sheets of paper one of which is loosely laid upon the other, one serving as a moisture proof lining for the other, and the package is wrapped in the 45 two sheets together as a sheet with a lining. The lining sheet is previously treated with some sort of preparation on both faces which has the characteristic of being dry and non-adhesive under normal atmospheric 50 conditions and which may be made adhesive by the application of heat so that said lining sheet will adhere both to the inner shell

itself and to the outer wrapping sheet throughout all portions of the contacting surfaces, and which will become dry and 55 preferably pliable as soon as it is allowed to cool, said substance with which the paper is treated having also the characteristic of making the lining sheet moisture proof.

The invention will be fully understood 60 by reference to the following description when taken in connection with the accompanying drawings and the novel features thereof will be pointed out and clearly defined in the claims at the close of this specification. 65

In the drawings, Figure 1 is a perspective view of a package having the lined wrapper folded about it in tubular form, two of the 70 corners showing the lining sheet turned back from the outer sheet merely to show that there are two sheets.

Fig. 2 shows the wrapper completely folded on the sides and on the bottom and partially folded at the top. 75

Fig. 3 is a perspective view showing the completely wrapped and sealed package.

Fig. 4 is a sectional view on line 4—4 of Fig. 3.

Fig. 5 is a sectional view of a portion of 80 the inner moisture proof or lining sheet of the wrapper before it is combined with the outer sheet.

Referring now to the drawings, 1 indicates the original unwrapped package which 85 is shown in dotted lines in Fig. 1 of conventional form. This package may be as previously stated a filled carton or a filled paper bag or box of any kind either sealed or unsealed. This may be made of very cheap 90 sheet material, all that is necessary being that it should be sufficiently strong to hold the material until it can be wrapped in the manner provided by the invention.

A sheet of paper 2 which will be ultimately 95 the outside layer of the completely wrapped and sealed package may have on one face thereof any necessary or desired printing which it is desired to have upon the outside of the finished package. This sheet of paper is spread out flat and there is then laid flat upon this sheet another sheet 3 preferably of the same size and shape as the sheet 2. This sheet 3 is properly prepared

before being laid upon the sheet 2. It may be treated after it is cut to the proper shape, or it may be cut from a large sheet which has been treated in a manner which will be 5 hereinafter described and which may be cut up to form blanks of the suitable size. This sheet 3 whether treated individually as a separate blank or while forming a part of a larger sheet just above described is treated 10 as follows. Both faces of the sheet are given a coat of substance, preferably in liquid or pasty form, which has the characteristic of adhering to or permeating the sheet 3 when the coating is applied hot and which 15 dries hard and pliable and remains hard but pliable under any natural conditions of the atmosphere either during the warmth of the summer or cold of the winter, but which when again heated to a high temperature, 20 that is a temperature above any natural condition of the atmosphere at any season of the year, will soften so that if pressure is applied to the overlying sheet while the coating is in the softened condition the two 25 sheets will be caused to adhere together, and once having adhered they will not separate without being heated again to the abnormal temperature.

One formula for a suitable preparation to 30 apply to the said inner sheet is as follows: one and one-half pounds of Burgundy pitch, 3 ounces of paraffin and eight one-hundredths of an ounce of rosin oil. The Burgundy pitch is melted first and then the 35 paraffin and rosin oil are added. A coating 4 of this mixture is applied to both faces of the sheet of paper 3 which is to be the lining sheet when said mixture is at a temperature considerably above any normal state of the 40 atmosphere, preferably at about 200° Fahr., and then the sheet is allowed to dry. Any resinous pitch may be used, and dry rosin may be used as a substitute for pitch, but it is preferable to use the Burgundy pitch 45 because the melting point is considerably lower than the rosin or other kinds of pitch so that when the sheet is applied to the package in combination with the outer sheet 1 a lower degree of heat is possible in sealing it than if the Burgundy pitch were 50 omitted.

In Fig. 5 the two surface layers of this preparation upon the sheet 3 are indicated by 4, 4 respectively.

55 In applying the wrapper, the sheet 3 having the upper and under layers 4, 4 is spread flat upon a sheet of the outer layer 2 upon a flat surface, and the package 1 is then wrapped up simultaneously in both sheets 30 of paper which are folded about it as though they were one sheet although there is no adhesion at this time between the sheets 2 and 3. After being wrapped, a hot presser device of some form, as for instance a hot 35 iron, like a flat iron, should be applied to

all parts of the outside of the wrapped package under pressure and for a sufficient length of time to thoroughly heat the coating upon the two surfaces of the sheet 3 which in the wrapped package now becomes 70 an intermediate sheet between the package 1 and the outer sheet 2. This heat softens the composition which has been applied to the sheet 3 and under pressure it will adhere to both the inner package and to the inner 75 sheet 2. When the hot pressure is removed the adhesive coating will dry and make a firm, permanent adhesion between the sheet 3 and both the inner package and the outer sheet. 80

If desired, instead of folding the wrapper complete before applying any heat, the heat and pressure may be applied to the sides after it is wrapped in tubular form as shown in Fig. 1, then the bottom may be folded 85 a shown in Fig. 2 and that may be sealed by applying the heat and pressure, and then the top may be folded and sealed. This however is a matter of option depending upon the convenience of the operator and 90 upon the sort of heating pressure device which is employed.

While I have given one formula for a preparation which may be used in treating the inner or lining sheet of the wrapper to 95 give it the proper adhesive characteristic and while I have stated also that one of the three ingredients, namely, Burgundy pitch, may be omitted, it is not intended herein to limit the invention to the use of a preparation according to the formula given either with or without the Burgundy pitch. It is intended that the claims shall be broad enough to cover the use of any suitable preparation which is capable of producing 100 the specified result, namely, any waterproof preparation which is adhesive at a temperature above all normal atmospheric temperatures and which is dry at all normal atmospheric temperatures. For instance the natural atmospheric temperature seldom rises above 100° Fahr. and fairly good success would be had with the use of a coating which might soften at 100° but in a hot climate and especially upon exposure to the sun the 110 atmospheric temperature sometimes rises above 100°. It is much safer to have the coating made of a preparation which will remain hard and dry until the temperature rises to at least 150° and still safer would 115 be a minimum temperature for softening at 200°. On the other hand it is desirable that the coating should be capable of softening and becoming adhesive without the necessity of too high a temperature so as to avoid the 120 expense of unnecessarily excessive heat which would also tend to burn the paper.

It is important that the coating on both sides of the inner or lining sheet should be left in a pliable condition as well as non- 125 130

sticky when it dries so that in the handling of the sheets the coating will not crack. The pitch is the base of the compound. Both the paraffin and the rosin oil aid in making it pliable. If the rosin or some equivalent thereof is omitted and paraffin alone is mixed with the pitch so much paraffin has to be used that the compound becomes too much of a paraffin compound and it is not sticky enough when hot to give the proper adhesion between the inner shell and the outside wrapper sheet. If the paraffin or some equivalent thereof is not used and if rosin oil alone is used with the pitch to render it pliable so much rosin oil has to be used to make the coating pliable that it makes the mixture non-drying when cool and the coated sheet will always be sticky in normal temperature. The use of both paraffin and rosin oil however keeps the coating in proper condition so that although it is sticky when hot, it is both pliable and non-sticky when cool or at their normal temperature.

In the process of wrapping and sealing the package according to the present invention there is absolutely no stickiness whatever in handling the package, the lining itself being dry and unsticky during all parts of the process when it could come in contact with the hands or with the machinery. During the time that it is in a sticky condition due to heat, it is out of hand touch, being entirely protected by the outer sheet and after the package is completely wrapped and sealed there is no stickiness whatever on the outside either under normal temperatures or when the package is heated sufficient to soften the coating on the lining. The outside appearance of the package is just the same as an un-waterproofed package and although when exposed to moisture, the moisture might permeate the outer sheet of the wrapper until it reached the outer coating of the lining, it cannot penetrate the lining, and therefore, the contents of the package and the inner shell itself are completely protected.

While I have stated that preferably the lining sheet is coated on both sides with the adhesive preparation so that it may be made to adhere both to the package and to the outer wrapping sheet, fairly good results may be obtained by coating one side only of the lining sheet so that by the application of heat under pressure the lining sheet may be made to adhere either to the outer wrapping sheet or to the package according to whichever side of the lining is coated.

It is also possible to obtain fairly good results if instead of employing two sheets the intermediate or lining sheet is omitted and the coating is applied directly to the inner face of the outer or wrapper sheet so that it will be made to adhere directly to the inner

shell upon the application of pressure and heat. Neither of the last two described forms of construction is so desirable or effective as the employment of the lining sheet coated on both sides, but I consider either of such additional constructions to come within the scope of the invention.

The moisture proof lining serves not only to protect the contents of the package against absorption of moisture from the outside, but it also serves to prevent the evaporation of moisture which is contained within the packaged goods and which it is desired to retain therein. Some kinds of package goods are intended to be dry when packed and kept dry. Other kinds of goods contain a certain amount of moisture which it is desired should be retained and the package of the present invention fulfills this requirement.

What I claim is:

1. A sealed, wrapped package comprising an inner closed shell which contains the goods, a wrapper consisting of an inner and an outer sheet wrapped and folded as a single lined sheet around said closed inner shell, the lining sheet of said wrapper having upon both faces a coating of moisture repellent adhesive material, said coating having the characteristic of being soft and sticky under a high degree of heat above natural atmospheric temperatures and being pliable and non-sticky under natural atmospheric temperatures, said lining sheet being adhesively attached throughout its surfaces to the contacting portions of both the inner shell and the outer sheet of the wrapper by means of said adhesive coating.

2. A sealed wrapped package comprising an inner closed shell which contains the goods, a wrapper consisting of an inner and an outer sheet wrapped and folded as a single lined sheet around said closed inner shell, the lining sheet of said wrapper having upon both its faces a coating of moisture repellent adhesive material, said coating having the characteristic of being dry and hard under all natural atmospheric temperatures and being soft and adhesive under a high degree of heat above natural atmospheric temperatures, said lining sheet being adhesively attached throughout its surfaces to the contacting portions of the inner shell and of said outer sheet by means of said adhesive coating.

3. A sealed wrapped package comprising an inner shell which contains the goods, and a wrapper folded about and sealed to said inner shell, said wrapper consisting of an outer sheet and a lining sheet, said lining being adhesively attached throughout one face to said outer sheet and throughout the contacting portion of its other face to said inner shell by means of a coating of moisture repellent adhesive material on both of said faces, said coating having the charac-

teristic of being moisture repellent and dry and hard under all temperatures which do not exceed at least 100° Fahr.

4. A sealed wrapped package comprising an inner shell which contains the goods, and a wrapper folded about and sealed to said inner shell, said wrapper consisting of an outer sheet and a lining sheet, said lining being adhesively attached throughout one face to said outer sheet and throughout the contacting portion of its other face to said inner shell by means of a coating of moisture repellent adhesive material on both of said faces, said coating consisting of a composition containing pitch, paraffin and rosin oil.

5. A sealed wrapped package comprising an inner shell which contains the goods, and a wrapper folded about and sealed to said inner shell, said wrapper consisting of an outer sheet and a lining sheet, said lining being adhesively attached throughout one face to said outer sheet and throughout the contacting portion of its other face to said inner shell by means of a coating of moisture repellent adhesive material on both of said faces, said coating consisting of a composition containing Burgundy pitch, paraffin and rosin oil.

30 6. A sealed wrapped package comprising an inner shell which contains the goods and a wrapper folded about and sealed to said inner shell, said wrapper consisting of an outer sheet and a lining sheet, said lining being adhesively attached throughout one face to said outer sheet and throughout the contacting portion of its other face to said inner shell by means of a coating of moisture repellent adhesive material on both of said faces, said coating consisting of a composition containing Burgundy pitch and another moisture repellent substance.

7. A sealed wrapped package comprising an inner shell which contains the goods and a wrapper folded about and sealed to said inner shell, said wrapper consisting of an outer sheet and a lining sheet, said lining being adhesively attached throughout one face to said outer sheet and throughout the contacting portion of its other face to said inner shell by means of a coating of moisture repellent adhesive material on both of said faces in substantially the following proportions, one and one-half pounds of Burgundy pitch, three ounces of paraffin, and eight one-hundredths of an ounce of rosin oil.

8. The method of forming a moisture proof wrapped and sealed package consisting of folding about an inner shell which contains the goods, a loose lined wrapper consisting of two sheets, one sheet of which is superimposed loose upon the other sheet before being wrapped, the two sheets then being wrapped and folded as one about the

said inner shell, so that one of said sheets forms a lining for the other sheet, said lining sheet having upon each face thereof a coating of moisture repellent adhesive material which has the characteristic of being dry and hard under natural atmospheric temperatures and which is soft and adhesive under a high degree of heat above the natural atmospheric temperature, subjecting the outer surface of the wrapped package to heat under pressure of sufficiently high temperature to soften said coating and cause the lining to adhere to both the inner shell and the outer sheet, and then allowing the package to cool.

9. The method of forming a moisture proof wrapped and sealed package consisting of folding about an inner shell which contains the goods, a wrapper having a sheet lining which has on both faces thereof a coating of moisture repellent adhesive material which has the characteristic of being dry and hard under at least all temperatures which are below 100° Fahr. and which softens under a high degree of heat at a temperature which is at least in excess of 100° Fahr. and subjecting the other surface of the wrapped package to heat sufficient to soften said adhesive and to pressure while so heated and then allowing the package to cool to a temperature below the hardening point.

10. The method of forming a moisture proof wrapped and sealed package consisting of folding about an inner shell which contains the goods, a wrapper having a sheet lining which has on both faces thereof a coating of moisture repellent adhesive material which has the characteristic of being dry and hard under at least all temperatures which are below 100° Fahr. and which softens under a high degree of heat at a temperature which is at least in excess of 100° Fahr. said coating consisting of a composition containing paraffin and rosin oil, and a pitchy substance, and subjecting the outer surface of the wrapped package to heat sufficient to soften said adhesive and to pressure while so heated and then allowing the package to cool to a temperature below the hardening point.

11. The method of forming a moisture proof wrapped and sealed package consisting of folding about an inner shell which contains the goods, a wrapper having a sheet lining which when the wrapper is being folded is unattached to the outer sheet and which has on both faces thereof a coating of moisture repellent adhesive material which has the characteristic of being dry and hard under at least all temperatures which are below 100° Fahr. and which is soft under a high degree of heat at a temperature which is at least in excess of 100° Fahr., said coating containing Burgundy pitch as one of its ingredients, subjecting the outer

surface of the wrapped package to heat sufficient to soften said adhesive and to pressure while so heated, and then allowing the package to cool to a temperature below the hardening point.

12. The method of forming a moisture proof wrapped and sealed package consisting of folding about an inner shell which contains the goods, a wrapper having a loose sheet lining which has on both faces thereof a coating of moisture repellent adhesive material which has the characteristic of being dry and hard under at least all temperatures which are below 100° Fahr. and which is soft under a high degree of heat at a temperature which is at least in excess of 100° Fahr., said coating composition containing Burgundy pitch, paraffin and rosin oil, subjecting the outer surface of the wrapped package to heat sufficient to soften said adhesive and to pressure while so heated and then allowing the package to cool to a temperature below the hardening point.

13. The method of forming a moisture proof wrapped and sealed package consisting of folding about an inner shell which contains the goods, a wrapper having a loose sheet lining which has on both faces thereof a coating of moisture repellent adhesive material which has the characteristic of being dry and hard under at least all temperatures which are below 100° Fahr. and which is soft under a high degree of heat at a temperature which is at least in excess of 100° Fahr., said coating composition containing Burgundy pitch, paraffin and rosin oil in substantially the following proportions, one and one-half pounds of Burgundy pitch, three ounces of paraffin and eight one-hundredths of an ounce of rosin oil, subjecting the outer surface of the wrapped package to heat sufficient to soften said adhesive and to pressure while so heated and then allowing the

package to cool to a temperature below the 45 hardening point.

14. A sealed wrapped package comprising a closed inner shell which contains the goods and a wrapper consisting of an inner and an outer sheet wrapped and folded as a lined 50 sheet around said closed inner shell, one of said sheets having upon at least one face thereof a coating of moisture repellent material, said coating having the characteristic of being soft and sticky under a high 55 degree of heat above natural atmospheric temperatures and being pliable and non-sticky under natural atmospheric temperatures, the sheet which is provided with said coating being adhesively attached to the entire 60 contacting surface of the other member or members of the package.

15. A sealed wrapped package comprising an inner closed shell which contains the goods, a paper wrapper folded around said 65 inner shell and a film of moisture repellent adhesive material between the wrapper and the inner shell, said film having the characteristic of being soft and sticky under a high degree of heat above natural atmospheric 70 temperatures and being pliable and non-sticky under natural atmospheric temperatures, the proximate surfaces of said package which contact with said film being adhesively connected together by said film. 75

16. A sealed wrapped package comprising an inner closed shell which contains the goods, a paper wrapper folded around said inner shell, and a film of moisture repellent adhesive material between the wrapper 80 and the inner shell, said film consisting of a composition containing pitch, paraffin and rosin oil, the proximate surfaces of said package which contact with said film being adhesively connected together by said film. 85

In testimony whereof I affix my signature.

SAMUEL B. FIELD.
